UNITED STATES PATENT OFFICE.

FREDERICK W. FISHER AND HARRY JOHNSON, OF DETROIT, MICHIGAN.

TOOTHPHBRUSH HOLDER.

Application filed April 1, 1922. Serial No. 548,607.

To all whom it may concern:

Be it known that we, FREDERICK W. FISHER and HARRY JOHNSON, citizens of the United States, and residents of Detroit, Wayne County, Michigan, have invented new and Improved Toothbrush Holders, of which the following is a specification.

This invention relates to containers especially adapted to protect tooth brushes from dust and other impurities when such brushes are not in use and its object is to provide a device of this character which can be cheaply constructed, which shall be strong and durable, and which will permit the ready insertion and withdrawal of the brushes.

In the accompanying drawing, Fig. 1 is a side elevation of this improved tooth brush holder. Fig. 2 is a horizontal section thereof. Fig. 3 is a vertical section of the bottom thereof. Fig. 4 is a perspective of the base. Fig. 5 is a perspective of one end of one form of partition. Fig. 6 is a similar view of another form of partition. Fig. 7 is a perspective of a retainer. Fig. 8 is a composite figure showing four different ways of cutting the retaining disk.

Similar reference characters refer to like parts throughout the several views.

This tooth brush holder consists of a cover 1 having a circumferential flange 2 which fits around the upper end of the shell 3. This shell may have any desired cross section, but is preferably cylindrical. The base 4 is preferably generally circular with a flange 5 to fit around the shell 3 and has a bracket 7 by means of which it may be attached to a wall or other support. This bracket may be of any desired size.

The base has a series of holes 8 and it supports a disk 9 of flexible material, rubber preferred, which is formed with slits or openings to permit the introduction of the brushes 13. In Fig. 8 the section 9^a is shown formed with a slit 10, the section 9^b with a square hole 11 and slits 12 extending therefrom, the section 9^c with a round hole 14 with slits 15 extending therefrom, and the section 9^d with a round hole 16 with slits 17 extending therefrom. The hole 11 and slits 12 are preferred, although the others are also satisfactory. Each of these slits can be expanded by the tooth brushes to permit them to be inserted. The resilience of the sheet 9

will hold the brushes in the shell but will 55 permit them to be withdrawn.

The disk 9 is held in position by a retainer 18 having holes 19 to register with the holes 8 in the base and this plate is held in position by the shell 3, cover 1 and the bolt 20 60 which has a nut 21 at its upper or lower end.

If desired, a partition may be mounted within the shell to divide the space between the brushes 13. In Fig. 5 is shown a four winged partition formed of the angle plates 65 24 and the strips 25 of blotting paper or other absorbent material between them. Tongues 26 may be formed on these plates to extend through holes 27 in other plates and thus unite them, the central hole 28 permitting the passage of the bolt 20. The absorbent strips 25 may be filled with a disinfecting liquid.

Another form of partition is shown in Fig. 6 to be formed of integral plates 30, the central portions being formed to produce a groove 31 to receive the bolt 20. In each case, the partition may be used to hold the plate 18 down against the disk 9 of resilient material. The partition shown in Fig. 75 6 may be of celluloid or any metal, the plate 18, the cover 1, the base 4 and the angle plates 24 are preferably of thin metal, while the shell may be of glass, celluloid, metal, wood or paper, but celluloid is preferred. 80 Notches 33 may be formed in the edges of this shell to permit ventilation.

The details of construction of this tooth brush holder may all be varied by those skilled in the art without departing from 90 the spirit of our invention as set forth in the following claim.

We claim:

A tooth brush holder consisting of a shell and means to close its upper end, a base to 95 support the shell, said base being formed with openings to admit the tooth brushes, a sheet of flexible material supported by the base and formed with slits which may be expanded by the tooth brushes to permit 100 their insertion, and a partition within the holder comprising upright walls extending between the openings in the base, said walls each consisting of two thin plates and a strip of material between them adapted to absorb 105 liquid disinfectant.

FREDERICK W. FISHER.
HARRY JOHNSON.
